Pittsburgh, Pa., a corporation of Pennsylvania

Application May 7, 1946, Serial No. 667,759

20 Claims. (Cl. 200—108)

1

This invention relates to circuit breakers and, more particularly, to circuit breakers of the type that are tripped automatically in response to overload currents.

An object of the invention is to provide a circuit breaker with an improved trip device having means for increasing the time delay tripping in response to higher value overload currents.

Another object of the invention is to provide a circuit breaker with an improved trip device embodying a mechanical escapement time delay having means for limiting the rate of escapement in response to higher value overload currents.

Another object of the invention is to provide a circuit breaker with an improved time delay trip device of the mechanical oscillator type embodying means for limiting the rate of oscillation of said device for higher value overload currents.

Another object of the invention is to provide a circuit breaker with an improved time delay trip device which is simple in construction, accurate and reliable in operation and inexpensive to manufacture.

The novel features that are considered characteristic of the invention are set forth in particular in the appended claims. The invention itself, however, both as to structure and operation, together with additional objects and advantages thereof, will be best understood from the following detailed description of a preferred embodiment thereof when read in conjunction with the accompanying drawings, in which:

Figure 1 is a vertical sectional view through the center pole of a multipole circuit breaker embodying a trip device constructed in accordance with the invention;

Fig. 2 is an enlarged detail view showing the mechanical escapement time delay device;

Fig. 3 is an enlarged front elevational view showing the time delay trip device;

Fig. 4 is a vertical sectional view taken substantially on line IV—IV of Fig. 3, and looking in the direction of the arrows;

Fig. 5 is a sectional view taken on the line V—V of Fig. 3, and showing the oscillator device.

Referring to Fig. 1 of the drawings, the circuit breaker is provided with an operating mechanism common to all of the poles of the breaker. The operating mechanism is mounted in a U-shaped frame 17 having sides which are rigidly connected by a cross member 19. The frame 17 is mounted on the central portion of

2

a base 11 of insulating material and is secured thereto by means of bolts 21 and 23. The outer ends of the frame are rigidly connected by a cross member 25.

The bolt 23 extends through the base and the cross member 19 and serves to rigidly secure a connector 27 of conducting material to the cross member 19 and to the frame. A shaft 29 extending through an opening in the connector 27 and through openings in the sides of the frame 17 pivotally supports a pair of contact arms 31 having their free ends integral with a contact arm 30 for the center pole. The contact arms (not shown) for the outer poles of the breaker are identical with the contact arm 30 for the center pole, but are not provided with arms 31. The contact arms are rigidly secured to a tie bar 67 which has an insulating cover 69 and extends across all of the poles and is securely clamped to the center pole contact arm 30 by means of a split clamp 70 and screw 71.

The movable contact structures and the stationary structures for the several poles are alike; hence only the contacts for the center pole are illustrated. The contact arm 30 pivotally carries a main movable contact member 47 and a movable arcing contact member 55 which cooperate respectively with a main stationary contact 39 and a stationary arcing contact 37. The stationary contacts 39 and 37 are secured to a conductor 41 which extends through an opening in the base 11 and forms a terminal connector 45. Contact pressure for the main contacts is provided by a spring 53 and a spring 63 provides contact pressure for the arcing contacts.

When the contact arm 30 is moved to open the contacts, the arc drawn across the arcing contacts 55—37 by rupture of the current is drawn into an arc extinguisher indicated generally at 76 where it is cooled and extinguished.

The movable arcing contact member 55 is connected by a flexible shunt conductor 77 to the main movable contact member 47, and another flexible shunt conductor 79 connects the contact member 47 to the connector 27. A conductor 81 secured to the connector 27 by means of bolts 74, extends downwardly therefrom rearwardly through the base to form the other terminal connector 83 which, together with the terminal connection 45, serves to connect the breaker in an electrical circuit.

The contact arms 30 are biased in a clockwise or opening direction by means of a pair of springs 85 (only one being shown). These springs are

tensioned between the center pole contact arm 30 and a fixed pivot 87 supported in the main frame 17. In the closed position of the breaker, the center pole contact arm and consequently all of the contact arms are releasably restrained in the closed contact position by means of a toggle and linkage mechanism which is collapsible to cause opening of the contacts.

This collapsible linkage includes a yoke shaped lever 89 pivotally mounted on a fixed pivot 91 supported on the main frame 17. The lever 89 is operatively connected to the support arms 31 of the center pole contact arm 30 by a main operating toggle comprising toggle links 93 and 95. The toggle link 93 has one end pivoted on a pin 101 supported on the lever 89, and the link 95 is pivoted on a pivot pin 99 in the arms 31. The links 93 and 95 are pivotally connected by a knee pivot pin 97. The toggle link 95 comprises a pair of links rigidly connected by means of an integral cross bar 115.

The free end of the lever 89 is pivotally connected by means of a link 103 to one arm of a lever 105 pivoted on the fixed pivot 87. The other end of the lever 105 is pivotally connected to a toggle link 107 of a tripping toggle comprising the link 107 and a toggle link 109. The link 109 is pivoted on a fixed pivot 113 supported on the frame 17 and comprises a pair of links joined near the pivot 113 by an integral yoke 123. The link 107 comprises a pair of links connected by an integral yoke 119 having a bent portion to which is secured an extension 121 of insulating material. The toggle links 107 and 109 are pivotally connected by a knee pivot pin 111. The purpose of the extension 121 is to cooperate with a part connected to a manually operable handle 141 to manually trip the breaker.

The above-described linkage serves to releasably hold the movable contacts for all of the poles of the breaker in closed contact position. In the closed position, the main operating toggle 93-95 is over center above a line through the centers of the pins 99 and 101, and a second toggle, one link of which comprises the overcenter links 93-95 and the other link of which comprises the lever 89, is over center above a line through the centers of the pins 99 and 91. The overcenter movement of the main operating toggle 93-95 is limited by the projecting end of the link 93 engaging the cross bar 115 of the link 95.

With the main operating toggle 93-95 and the toggle comprising the links 93-95 and the lever 89 in the overcenter position, the springs 85 bias the lever 89 in a clockwise direction. Clockwise movement of the lever 89, however, is normally prevented by the tripping toggle 107-109 which is over center to the left of a line through the center of the fixed pivot 113 and the point of connection of the link 107 with the lever 105. A spring 128 tensioned between the yoke 119 and the fixed pivot 113 biases the tripping toggle to its overcenter position. The overcenter position of the tripping toggle 107-109 is adjustably determined by the projection 125 of the yoke 123 engaging an adjusting screw 129.

The tripping toggle 107-109 is adapted to be moved over center outwardly in a direction to cause its collapse to effect opening of the contacts by means of an overload trip device indicated generally at 133, or by a shunt trip device indicated generally at 138. The overload trip device 133 is operable in response to overload currents in the circuit of the breaker to actuate a

trip rod 135 and cause collapse of the tripping toggle 107-109. The shunt trip device is adapted to be energized from any suitable source separate from the circuit of the breaker to actuate a tubular trip member 140 surrounding the trip rod 135 and cause the collapse of the tripping toggle 107-109 independently of the operation of the trip rod 135.

When operated by their respective trip devices 133 or 138, the trip rod 135 or the trip member 140 strikes the projection 127 of the yoke 123 and rocks the toggle link 109 clockwise about the fixed pivot 113. This movement of the link 109 causes collapse of the tripping toggle 107-109 permitting clockwise movement of the lever 89 which permits the springs 85 to actuate the movable contact structure clockwise to open the contacts.

The main operating toggle 93-95 does not immediately collapse, but the force of the springs 85 applied through the contact arms 30-31 and the main operating toggle causes collapse of the toggle comprising the links 93-95 and the lever 89 which results in a clockwise movement of the lever 89. This movement is transmitted through the link 103 and the lever 105 to complete the collapse of the tripping toggle 107-109.

The clockwise or opening movement of the contact arms 30-31 is arrested by projections (not shown) thereon striking the frame 17. At this time, the rebound of the inertia of the main operating toggle 93-95 and the parts of the linkage 89, 103 and 105 starts the main operating toggle 93-95 over center in a direction to cause its collapse. By the time the knee pin 97 of the toggle has passed over center below the line 99-101, the weight of the parts acts to complete the collapse of the toggle 93-95 and causes the linkage 89, 103, 105 and the tripping toggle to be automatically reset to their normal holding positions. The main toggle 93-95 remains in collapsed condition until the contacts are closed.

The contacts are closed manually by clockwise rotation of the handle 141. This movement of the handle, through connections not shown, thrusts a link 151 downwardly, and, due to the engagement of the link with a projection 153 on a yoke shaped closing lever 145, rotates the closing lever in a clockwise direction. The closing lever 145 comprises a pair of spaced levers disposed on the outside of the frame 17 and are pivotally supported on the fixed pivot 91. Clockwise movement of the closing lever 145 engages a roller 155 pivotally carried on the inner end of the lever with the toggle link 93 now in its collapsed position and moves the toggle 93-95 to its overcenter position. Since at this time the tripping toggle 107-109 has been restored to its overcenter holding position, rotation of the lever 89 is prevented, and consequently the force applied by the roller 155 to straighten the operating toggle 93-95 rotates the contact arms 30 counterclockwise to close the contacts and tension the springs 85.

The handle 141 is restored to its normal position by means of a spring 159 tensioned between the closing lever 145 and the frame 17. Upon release of the handle following a closing operation, the spring 159 moves the closing lever 145 counterclockwise and, through the projection 153 and link 151, restores the handle 141 to its normal position.

The circuit breaker may be tripped manually by rotation of the handle 141 through a small angle in a counterclockwise direction from its neutral position. Rotation of the handle 141 in tripping

direction engages a projection (not shown) on the link 151 with the extension 121 on the yoke 119 of the tripping toggle link 107 and rocks the link counterclockwise about its point of connection with the lever 141 and rocks the link counterclockwise about its point of connection with the lever 105. This moves the tripping toggle 107—109 over center in tripping direction and effects opening of the contacts in the previously described manner.

As previously set forth, the trip rod 135 is operated to effect collapse of the tripping toggle 107—109 by means of the current-responsive trip device 133. There is a trip device 133 provided for each pole of the breaker, but since the trip devices are alike only the one associated with the center pole will be described.

The trip device 133 includes a U-shaped magnet core 161 and a U-shaped frame comprising side plates 163 rigidly connected by an integral cross member 165. The frame 163 is provided with inwardly formed feet 167, and bolts 169 passing through openings in the feet 167 and the core member 161 rigidly secure these parts to the base 11. An armature 179 which cooperates with the core member 161 is mounted in one end of a trip lever 173 pivotally mounted on a pivot pin 175 supported in the frame 163. The trip lever 173 comprises a pair of levers rigidly connected at their right-hand ends by an integral yoke 177. The yoke 177 carries a screw 181 which, upon operation of the trip lever 173, moves the trip rod 135 upwardly to effect tripping of the breaker in the manner previously set forth. The magnet core 161 is energized to attract the armature 179 and operate the trip lever 173 by overload currents flowing in the circuit of the breaker including the conductor 81 which, as illustrated, passes between the legs of the U-shaped core 161. Normal rated current traversing the conductor 81 does not energize the core member 161 enough to overcome the tension of a pair of biasing springs 191 (only one being shown) having one end attached to the yoke 177 and the other end attached to a movable adjusting member 193 threadedly engaged by an adjusting screw, the knurled head 197 of which bears against the bottom of the cross member 165. Rotation of the screw moves the member 193 to adjust the tension of the springs, thereby varying the minimum overload tripping point of the breaker. The springs 191 normally bias the yoke 177 of the trip lever 173 against a stop screw 204 which determines the open air gap of the magnet.

A trip bar 187 is rotatably mounted in arms 188 of a bracket 189 (Fig. 3) secured to a U-shaped frame 157 of the shunt trip device 138. The frame 157 which is of magnetic material is secured by means of screws 183 to flange portions 195 integral with the main frame 17. The frame 157 is also secured to and spaced from a front plate 199 by means of a bar 201 and screws 203, the front plate being secured to an insulating bracket 143 suitably secured to the main frame 17. The trip bar 187 extends across all of the poles of the breaker and is provided with a plurality of arms 185 secured thereto by means of screws 207; there being an arm 185 for each pole, only the one associated with the center pole is bifurcated and straddles the lower end of the trip rod 135 between flanges 205 secured to the trip rod, one above and one below the arm 185. It can thus be seen that operation of the trip bar 187 by the trip device 133 for any pole of the breaker also operates the center pole arm 185.

which thrusts the trip rod upwardly to trip the breaker. A spring 209, has one end hooked over a spring stud 211 carried by a lever 215 pivotally mounted on the trip bar 187 and forming a part of the time delay means, and the other end of the spring is anchored to a spring stud 213 secured to the arm 185 for the center pole of the breaker. The spring 209 thus biases the trip bar 187 and all of the arms 185 in a counterclockwise direction to 10 the position shown in Fig. 1, where a reduced portion of the stud 213 engages a shoulder 216 on the lever 215.

The arms 188 of the bracket 189 are rigidly connected by an integral cross member 190 which 15 is secured by means of screws 217 to the bottom leg of the U-shaped frame 157. The screws 217 also serve to secure a member 219 to the center portion 190 of the bracket 189 and to the frame 157. The right-hand arm 188 (as viewed in Figure 3) of the bracket 189 has a U-shaped bracket 221 secured thereto by means of bolts 223 and nuts 225.

The lever 215 is provided with an arcuate rack 227 (Fig. 4) the teeth of which mesh with a 25 pinion 229 rotatably mounted on a shaft 231, supported in the two arms of the bracket 221. The pinion 229 is rigidly connected by means of a sleeve 233 to an escapement wheel 235 also supported for rotation on the shaft 231. The escapement wheel 235 is provided with teeth around 30 a portion of its periphery and these teeth engage spaced projections 237 on an oscillator bar 239 which is mounted for oscillatory movement on a shaft 241 supported in the spaced legs of the bracket 221. Two oscillator plates 243 and 245, disposed one on each side of the oscillator bar are pressed into frictional contact with the sides of the oscillator bar near the ends thereof by 35 means of springs 247 and 249, respectively. The springs 247 and 249 surround the shaft 241 and are compressed between collars 251 and 253, respectively, secured to the shaft 241, and the corresponding oscillator plates 243 and 245.

When an overload current of relatively low 40 value, up to, for instance, 400% of normal rated current, occurs in the circuit through any pole of the breaker, the armature 179 (Fig. 1) for that pole is attracted and applies a force tending to rotate the arm 185 and the trip bar 187 in a clockwise direction. This force is applied through the strong spring 209, but without stretching the spring, to the lever 215 urging this lever in a clockwise direction (Fig. 4) about its pivot. The lever 215, through the rack 227 and pinion 229 rotates the escapement wheel 235 in a counterclockwise direction setting the oscillator 239 in motion, the rotation of the escapement wheel 235 and the speed of operation of the trip device being retarded by the alternate engagement of 45 the projections 237 of the oscillator 239 with the teeth of the escapement wheel 235. The retarding action of the escapement device will continue until the last tooth of the escapement wheel, indicated at 255 (Figs. 2 and 4) escapes the left-hand projection 237 of the oscillator bar 239 (as viewed in Fig. 2), whereupon the armature 179 (Fig. 1) acts to quickly move the trip rod 135 upwardly to trip the breaker in the previously described manner.

A relatively light spring 259 (Fig. 3) having one end anchored to a spring stud 261 on the arm 185 for the center pole and the other end anchored on a spring stud 263 on the bracket 157 is provided to bias the trip bar 187 and the lever 215 counterclockwise to their normal

unoperated positions (Fig. 1) and to restore the trip bar and the mechanical escapement device to normal position following a time delay tripping operation. During the resetting operation the spring 259, acting through the arm 185 and pin 213, rotates the lever 215 counterclockwise to the position in which it is shown in Fig. 4. Counterclockwise movement of the lever 215 and the rack 227 rotates the pinion 229 and the escapement wheel 235 in a clockwise direction to the normal position. The oscillator 239 imposes but little restraining action on the wheel 235 during the resetting movement due to the relatively light forces involved.

On higher value overload currents below the instantaneous tripping point of the breaker, the armature 179 is attracted with a much greater force and operates the escapement device at much higher rate of speed with a consequent reduction in the amount of time delay. In certain instances, it is desirable to provide a greater amount of time delay in the intermediate range of overload currents, for instance, between 400% and 1000% of rated current. To this end, the oscillator plates 243 and 245 are provided and are pressed into frictional engagement with the oscillator bar 239 by the springs 247 and 249, respectively. In response to overload currents in the low range of overload currents, that is, up to approximately 400% of rated current, the oscillator bar 239 and the oscillator plates 243 and 245 oscillate as a mass since the force involved is insufficient to cause relative movement between the bar 239 and the plates 243, 245. In the intermediate range of overload currents, however, the force applied by the escapement wheel 235 to the oscillator bar 239 causes the latter to oscillate rapidly. At a critical force the oscillator plates 243 and 245 start to slide relative to the oscillator bar 239 thus introducing frictional losses which impose additional restraint on the escapement wheel and reduce the rate of oscillation. Since the plates 243—245 oscillate through a greater angle than the oscillator bar 239, the average mass of the oscillator assemblage oscillates through a greater angle than the bar 239 further reducing the rate of oscillation. This reduced rate of oscillation delays tripping of the breaker, in response to overload currents in the intermediate range, for a longer time than if the plates 243 and 245 were not free to move relative to the oscillator bar 239.

The movement of the plates 243 and 245 relative to the oscillator bar 239 is limited by pins 256 mounted in the oscillator bar 239 and extending to each side thereof through arcuate slots 257 in the plates 243 and 245. At or near the maximum degree of oscillation, the pins 256 engage the ends of the slots 257 thus limiting the relative movement of the plates 243 and 245 and the bar 239 and imposing additional restraint on the bar.

It will be obvious that the springs 247, 249 may be omitted and the increased time delay on overload currents in the intermediate range provided by permitting the pins 256 to drive the plates 243, 245.

When an overload current of 1000% of rated current or over, or a short circuit occurs, the armature 179 actuates the trip bar with sufficient force to stretch the spring 209 and to operate the trip rod 135 to instantaneously trip the breaker.

The shunt trip device 138 comprises a solenoid having an energizing winding 260 and a movable

core (not shown) which is secured to the tube 140. The winding 260 may be energized from any source by either a manually or automatically controlled switch (not shown). When the winding 260 is energized, the movable core (not shown) is attracted upwardly moving the tube 140 therewith to engage and operate the tripping toggle 107—109 and trip the breaker.

It will be understood by those skilled in the art that the operating characteristics of the trip device may be varied by changing the design of the electromagnet and also by changing the strength of the springs. The limits of the ranges of overload current values set forth above are to be considered merely by way of example, and these limits may be varied to suit particular requirements.

From the foregoing it will be apparent that the instant invention provides an improved time delay trip device having an improved time-current tripping curve on overload currents in the intermediate range without affecting the low overload time delay or the instantaneous tripping.

Having described the invention in accordance with the patent statutes, it is to be understood that various changes and modifications may be made in the structural details and combination of elements disclosed without departing from some of the essential features of the invention. It is, therefore, desired that the language of the appended claims be given as reasonably broad interpretation as the prior art permits.

I claim as my invention:

1. In a circuit breaker comprising relatively movable contacts and operating means therefor, an electromagnetic trip device operable to cause automatic operation of said operating means comprising an energizing winding, an armature movable to cause tripping of the breaker, time delay means for retarding operation of said trip device in response to overload currents of predetermined value, and a member frictionally engaging said time delay device and movable relatively thereto in response to overload currents above said predetermined value to further retard operation of said trip device.

2. In a circuit breaker comprising relatively movable contacts and operating means therefor, a trip device comprising an electromagnet having a movable armature operable to trip the breaker, a time delay device operatively related to said trip device for at times retarding operation of said armature, and a member biased into engagement with said time delay device and frictionally movable relative thereto when said trip device is operated in response to overload currents of predetermined value to increase the retarding action of said time delay device.

3. In a circuit breaker comprising relatively movable contacts and operating means therefor, a trip device comprising an electromagnet and an armature movable to trip the breaker, a time delay device comprising a mechanical escapement device for retarding tripping movement of said armature, and a mass frictionally engaging said mechanical escapement and operable in response to predetermined overload currents to increase the retarding action of said mechanical escapement.

4. In a circuit breaker comprising relatively movable contacts and operating means therefor, a trip device comprising an electromagnet and an armature movable to trip the breaker, a time delay device comprising a mechanical escape-

ment device for retarding tripping movement of said armature, and a mass frictionally related to said mechanical escapement and movable relative thereto in response to predetermined overload currents to increase the retarding action of said mechanical escapement, said trip device being operable at times independently of said time delay device to instantaneously trip the breaker.

5. In a circuit breaker comprising relatively movable contacts and operating mechanism therefor, a trip member operable to cause automatic operation of said operating mechanism, trip means operable in response to overload currents to operate said trip member, a time delay device comprising a mechanical escapement mechanism and an oscillator operable to retard tripping operation of said trip member, and a member biased into frictional engagement with said oscillator operable in response to overload currents of predetermined value to reduce the rate of oscillation of said oscillator.

6. In a circuit breaker comprising relatively movable contacts and operating mechanism therefor, a trip member operable to cause automatic operation of said operating mechanism, an electromagnetic trip device operable in response to overload currents to operate said trip member, a time delay device including oscillating means operable to retard tripping operation of said trip device, and a member engaging said oscillating means for at times automatically increasing the extent of the effective oscillation of said oscillating means to thereby increase the retarding action of said time delay means.

7. In a circuit breaker comprising relatively movable contacts and operating mechanism therefor, a trip member operable to cause automatic operation of said operating mechanism, an electromagnetic trip device operable in response to overload currents to operate said trip member, a time delay device including oscillating means operable to retard tripping operation of said trip device, and a member cooperative with said oscillating means for at times automatically increasing the extent of the effective oscillation of said oscillating means to thereby increase the retarding action of said time delay means, and said trip member being operable at times independently of said time delay means to instantaneously trip the breaker.

8. In a circuit breaker comprising relatively movable contacts and operating mechanism therefor, a trip device operable to cause automatic operation of said operating mechanism, a time delay device operable to retard operation of said trip device, comprising an oscillator having a predetermined rate of oscillation in response to overload currents of predetermined value and a higher rate of oscillation in response to overload currents above said predetermined value, and a member engaging said oscillator for movement therewith in response to overload currents of said predetermined value and movable relative to said oscillator in response to overload currents above said predetermined value to automatically reduce the rate of oscillation of said oscillator to thereby increase the retarding action of said time delay device.

9. In a circuit breaker comprising relatively movable contacts and operating mechanism therefor, an electromagnetic trip device operable to cause automatic operation of said operating mechanism, time delay means comprising an oscillator operable to retard tripping operation of said trip device, and means disposed in fric-

tional relation to said oscillator and movable relative to said oscillator in response to overload currents of predetermined value to retard operation of said oscillator to thereby increase the retarding action of said time delay means.

10. In a circuit breaker comprising relatively movable contacts and operating mechanism therefor, an electromagnetic trip device operable to cause automatic operation of said operating mechanism, time delay means comprising an oscillator operable to retard tripping operation of said trip device, and a member disposed in frictional relation to said oscillator and movable relative to said oscillator in response to overload currents of predetermined value to retard operation of said oscillator to thereby increase the retarding action of said time delay means.

11. In a circuit breaker comprising relatively movable contacts and operating mechanism therefor, an electromagnetic trip device operable to cause automatic operation of said operating mechanism, time delay means comprising an oscillator operable to retard tripping operation of said trip device, and a plurality of members disposed in frictional relation to said oscillator and movable relative to said oscillator in response to overload currents of predetermined value to retard operation of said oscillator to thereby increase the retarding action of said time delay means.

12. In a circuit breaker comprising relatively movable contacts and operating mechanism therefor, an electromagnetic trip device operable to cause automatic operation of said operating mechanism, time delay means comprising an oscillator operable to retard tripping operation of said trip device, and means disposed in frictional relation to said oscillator and movable relative to said oscillator in response to overload currents of predetermined value to retard operation of said oscillator to thereby increase the retarding action of said time delay means, and spring means providing frictional pressure between said means and said oscillator.

13. In a circuit breaker comprising relatively movable contacts and operating mechanism therefor, an electromagnetic trip device operable to cause automatic operation of said operating mechanism, time delay means comprising an oscillator operable to retard tripping operation of said trip device, and a member disposed in frictional relation to said oscillator and movable relative to said oscillator in response to overload currents of predetermined value to retard operation of said oscillator to thereby increase the retarding action of said time delay means, and spring means providing frictional pressure between said member and said oscillator.

14. In a circuit breaker comprising relatively movable contacts and operating mechanism therefor, an electromagnetic trip device operable to cause automatic operation of said operating mechanism, time delay means comprising an oscillator operable to retard tripping operation of said trip device, and a plurality of members disposed in frictional relation to said oscillator and movable relative to said oscillator in response to overload currents of predetermined value to retard operation of said oscillator to thereby increase the retarding action of said time delay means, and a plurality of springs providing frictional pressure between said members and said oscillator.

15. A circuit breaker comprising relatively movable contacts and operating means therefor,

a trip device operable to cause automatic operation of said operating mechanism, time delay means comprising a mechanical escapement having an oscillator operable to retard tripping operation of said trip device, a member disposed in frictional relation with said oscillator, said oscillator and said member oscillating as a unit in response to overload currents of predetermined value to retard tripping operation of said trip device at a predetermined rate, and said oscillator and said member oscillating relative to each other in response to overload currents above said predetermined value to reduce the rate of oscillation of said oscillator.

16. A circuit breaker comprising relatively movable contacts and operating means therefor, a trip device operable to cause automatic operation of said operating mechanism, time delay means comprising a mechanical escapement having an oscillator operable to retard tripping operation of said trip device, a member disposed in frictional relation with said oscillator, spring means providing frictional engagement between said oscillator and said member, said oscillator and said member oscillating as a unit in response to overload currents of predetermined value to retard tripping operation of said trip device at a predetermined rate, and said oscillator and said member oscillating relative to each other in response to overload currents above said predetermined value to reduce the rate of oscillation of said oscillator.

17. A circuit breaker comprising relatively movable contacts and operating means therefor, a trip device operable to cause automatic operation of said operating mechanism, time delay means comprising a mechanical escapement having an oscillator operable to retard tripping operation of said trip device, a member disposed in frictional relation with said oscillator, said oscillator and said member oscillating as a unit in response to overload currents of predetermined value to retard tripping operation of said trip device at a predetermined rate, and said oscillator and said member oscillating relative to each other in response to overload currents above said predetermined value to reduce the rate of oscillation of said oscillator, and means for limiting relative movement between said oscillator and said member.

18. A circuit breaker comprising relatively movable contacts and operating means therefor, a trip device operable to cause automatic operation of said operating mechanism, time delay means comprising a mechanical escapement having an oscillator operable to retard tripping operation of said trip device, a member disposed in frictional relation with said oscillator, spring means for pro-

viding frictional engagement between said oscillator and said member, said oscillator and said member oscillating as a unit in response to overload currents of predetermined value to retard tripping operation of said trip device at a predetermined rate, said oscillator and said member oscillating relative to each other in response to overload currents above said predetermined value to reduce the rate of oscillation of said oscillator, and means for limiting relative movement between said oscillator and said member.

19. In a circuit breaker comprising relatively movable contacts and operating mechanism therefor, a trip device operable to cause automatic operation of said operating mechanism, time delay means comprising a mechanical escapement mechanism including an oscillator operable to retard tripping operation of said trip device, a member disposed in frictional relation with said oscillator and movable with said oscillator in response to overload currents to retard tripping operation of said trip device, said member at times being movable relative to said oscillator to increase the amount of time delay for a given value of overload current.

20. In a circuit breaker comprising relatively movable contacts and operating mechanism therefor, a trip device operable to cause automatic operation of said operating mechanism, time delay means comprising a mechanical escapement mechanism including an oscillator operable to retard tripping operation of said trip device, a member disposed in frictional relation with said oscillator and movable with said oscillator in response to overload currents to retard tripping operation of said trip device, said member at times being movable relative to said oscillator to increase the amount of time delay for a given value of overload current, and means for limiting the movement of said member relative to said oscillator.
